UNITED STATES PATENT OFFICE.

EDWIN T. WADE, OF JACKSON, MISSISSIPPI, ASSIGNOR OF ONE-THIRD TO ALBERT C. JONES, OF JACKSON, MISSISSIPPI.

RAIL TIE AND FASTENER.

1,348,460.

Specification of Letters Patent.

Patented Aug. 3, 1920.

Application filed December 30, 1919. Serial No. 348,260.

To all whom it may concern:

Be it known that I, EDWIN T. WADE, a citizen of the United States, residing at Jackson, in the county of Hinds and State of Mississippi, have invented a new and useful Rail Tie and Fastener, of which the following is a specification.

This invention relates to railway track construction, and more particularly to the tie construction thereof.

The primary object of the invention is to provide a concrete or composition tie construction having means to properly reinforce the same throughout the length thereof, of which reinforcing elements support the rails associated with the tie, thus eliminating any possibility of the tie breaking or being rendered inoperative under the strain of trains passing thereover.

A further object of the invention is to provide means forming a part of the tie for securing the rail to the tie, thus insuring against displacement of the rail supported thereon.

A further object of the invention is to provide a rail tie which embodies certain improvements on my prior application allowed Oct. 15, 1919, and which includes reinforcing elements passing downwardly through the tie.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of which is claimed, without departing from the spirit of the invention.

Referring to the drawings:

Figure 1 illustrates a plan view of a railway tie constructed in accordance with the present invention;

Fig. 2 illustrates a side elevational view of the same;

Fig. 3 illustrates a side elevational view of a modified form of rail chair and securing means, and

Fig. 4 illustrates a perspective view of one of the end caps.

Fig. 5 illustrates a sectional view taken on line 5—5 of Fig. 1.

Referring to the drawings in detail, the device is shown as including sections 5 and 6,

which are formed of concrete or other plastic material, and include the reinforcing bars 7, which are embedded in the upper surface of each of the sections 5 and 6, the bars being arranged in parallel relation with each other, and in spaced relation with the side edges of the respective sections, the thickness of each of the bars 7 being great enough to permit a substantial portion of the bars to be embedded within the concrete structures, and at the same time permit the upper surfaces thereof to lie flush with the upper surfaces of the respective sections 5 and 6.

These bars 7, are preferably formed of malleable iron and are substantially wide, the same being of lengths equal to the combined length of the sections 5 and 6, so that the ends of the bars 7 will lie flush with the ends of the respective sections, the inner ends of the respective sections being spaced apart as at 8, but having connection with each other, through the portions 9 of the bars 7, which portions 9 support the sections 5 and 6 in proper spaced relation with each other, and prevent lateral displacement of the sections.

In the construction of each of the sections, tapering openings are formed on the undersides of the respective sections, the openings being disposed adjacent the outer ends of the sections, and receive the angularly tapering heads 11 of the securing bolts 12, which are of lengths to permit the same to pass the entire distance through the sections, the upper ends thereof passing through suitable openings provided in the bars 7, the nuts 13 being positioned on the upper ends of the securing bolts for securing the bars 7 to the sections 5 and 6, to prevent the same from moving with relation to the sections forming a part thereof.

Similar securing bolts 14, pass upwardly through the respective sections 5 and 6, and each of the securing bolts 14 includes an angularly tapering nut 15, threaded internally to receive the threaded extremity 16 of the securing bolt, the upper end of each securing bolt passing through a suitable opening in the section associated therewith. The upper end of each securing bolt has a squared head 17 formed integral therewith, which head in operation contacts with a rail fastener 18, which is also apertured to receive a portion of the bolt associated

therewith, the same having an extension 19 embracing the lower edge, or flange of the rail 19' to be secured to the tie. It will thus be seen that upon rotation of the head 5 17, the nut 15 is moved within its opening, with the result that the rail fastener 18 is secured in position.

While I have shown and described one 10 element of the fastening means, it is of course understood that a similar construction is provided on the opposite edge of the flange of the rail.

Reinforcing end plates 20, embrace the 15 adjacent ends of the plastic sections 5 and 6, and as shown, these end plates include parallel members 21 and 22, spaced apart, the distance between the members 21 and 22 being equal to the thickness of the respective sections so that these end plates will 20 exactly fit over the ends of the sections thus eliminating any movement between the sections and reinforcing elements, which would tend to wear the sections at their points of contact with the end plates.

Disposed within the parallel members 21 and 22 at the points directly opposite each other are the openings 23, which openings receive the bolts 24 for securing the end plates 20 to the respective sections, a nut 25 30 operating on one end of each of the bolts 24 for accomplishing this result.

The end plates 20, are also provided with 35 openings to permit the bars 7 to pass therethrough, so that the sections 5 and 6 will prevent lateral movement of the end plates 20 with relation to the sections, to aid in the bracing of the section.

In the modified form of the invention, as illustrated by Fig. 3 of the drawings, a rail

chair 10' is provided, which rail chair has 40 upwardly extending flanges 11' of a length to extend above the heads 17 to permit the flanges 11' to be bent over the heads 17 to lock the bolts 14 against rotation.

Having thus described the invention, what 45 I claim as new is:—

1. In a railway tie construction, opposed 50 sections of plastic material, reinforcing elements disposed in the upper surface of both of the sections, and providing means to connect the sections, end plates including parallel members contacting with the upper and lower surfaces of the respective sections, said end plates having openings to accommodate the reinforcing elements, and rail 55 securing means extending through each of the opposed sections.

2. In a railway tie construction, opposed 60 sections of plastic material, relatively flat reinforcing elements, disposed in the upper surface of both of the sections, and providing means for connecting the sections, end plates embracing the respective sections, said end plates having openings to accommodate the reinforcing elements, rail securing 65 means supported by the respective sections, and means extending through the respective sections and having connection with the rail securing means for securing the rail securing means to the respective 70 sections.

In testimony that I claim the foregoing as my own I have hereto affixed my signature in the presence of two witnesses.

EDWIN T. WADE.
